UNITED STATES PATENT OFFICE.

ABRAHAM SCHOEN, OF CHICAGO, ILLINOIS, ASSIGNOR TO SUPERIOR BRASS AND FIXTURE CO., OF CHICAGO, ILLINOIS.

LIGHTING-FIXTURE.

1,127,527.

Specification of Letters Patent.

Patented Feb. 9, 1915.

Application filed March 7, 1914. Serial No. 833,097.

To all whom it may concern:

Be it known that I, ABRAHAM SCHOEN, a citizen of the United States, residing at Chicago, in the county of Cook and State of Illinois, have invented certain new and useful Improvements in Lighting-Fixtures, of which the following is a specification.

This invention relates to suspended electric light fixtures in which a cluster of 10 incandescent bulbs are used.

The main object of this invention is to provide a simple, durable, economical, and efficient light fixture which will furnish the maximum amount of illuminative value and 15 candle power.

A further object of the invention is to provide a highly ornamental glass bowl of novel construction and possessing special diffusive qualities, which bowl is provided 20 with means whereby it may be readily removed for proper cleaning from all other portions of the fixture.

Another object of this invention is to furnish a novel light suspending device in 25 which the incandescent electric lights are arranged in nests or groups within a light diffusing bowl, each light being removably secured to a metal ring or band on a plane parallel with the said ring or band and with 30 the upper portion of the bowl.

A still further object is to so mount the electric bulbs on a metal ring or band suspended by a plurality of chains within the inside face of the bowl that they will furnish the most efficient results, and at the 35 same time be compact, neat and occupy very little space.

The foregoing and such other objects as may occur from the ensuing description, are 40 attained by the means hereinafter more fully described, and by the combination, construction, arrangement and location of the parts such as illustrated in the accompanying drawings, and particularly set forth in the claims appended hereto.

Reference now being had to the accompanying drawings which form a part of this specification and in which similar letters of reference indicate like parts throughout the 50 several views, it will be seen that: Figure 1, is a view partly in perspective and partly in side elevation showing the suspended fixture embodying the invention. Fig. 2, is a cross section through the suspending chains

illustrating a plan view of the improved 55 light fixture. Fig. 3, is a cross sectional elevation of the lighting fixture showing the bowl disconnected and suspended from its supporting ring. Fig. 4, is a detail perspective view showing a portion of the supporting ring, means secured to said ring by which it is supported by the chains, and a portion of the supporting means for one of the light bulbs secured thereto, and Fig. 5, is a sectional view taken on the line $\alpha-\alpha$, 60 55 Fig. 4.

It will be perceived that the fixture is hung from above by a plurality of chains, and is provided with a metal ring which supports both the electric lamps and the 70 light diffusing bowl, the latter being made of pieces of glass laid in coppered mosaic, and in case of breakage any one or number of small pieces of the glass can be replaced at a nominal expense. 75

The numeral 1, designates a canopy ceiling fixture or inverted cap which is attached to or arranged adjacent to the ceiling of a room so as to conceal the manner of attachment as well as the lead wires to 80 the electric lamps, and 2 represents a plurality of eye pieces or similar devices secured to said canopy, adapted to provide a means for attaching to said ceiling fixture 1 suitable suspension means 3, such as chains 85 or the like, which are adapted to support or suspend in proper position a metal ring 4, said ring supporting a cluster or plurality of electric lamps 5, and the light diffusing bowl 6 in the manner hereinafter described. The said ring 4, is formed with a plurality of internally projecting bends or loops 7, and within each bend or loop is fixedly secured to the ring by brazing or in any other suitable manner a suspension 90 member 8, by means of which the said ring is properly connected with the said suspension means 3. The said suspension member 8 is formed of a single piece of metal having an eye portion 9, a body portion 10 provided with an annular shoulder 11 and a depending threaded portion 12. 95

It will be observed that each inwardly projecting bend or loop of the ring 4 rests upon and is supported by the shouldered 100 portion 11 of the member 8; said member being fixedly secured thereto, and to the depending threaded portion 12 beneath the 105

shouldered portion 11 of the member 8, is secured by a nut 13, a metal bar 14 provided with an opening in its rear portion adapted to be fitted around the threaded portion 12 of the member 8, the front portion of said bar 14 being suitably secured to the rear portion of each electric lamp 5, whereby said lamps are firmly held and supported on a plane parallel with the said supporting ring 4.

10 The light diffusing bowl 6 is surrounded at its upper portion with a metallic rim 15, said rim being provided with a plurality of inwardly projecting integral hooks 16, and 15 a plurality of inwardly extending integral projections 17, each projection 17 being provided with a perforation therethrough adapted to receive the lower hooked end portion 18 of a bowl suspending chain 19, 20 the upper end of each chain being suitably secured at 20 to the metal supporting ring 4, whereby when the ring is removed from beneath the inwardly projecting hooks within the bowl, said bowl will be entirely re- 25 moved from all other portions of the fixture and will be suspended by the chains 19 at a suitable distance below the fixture to permit the bowl to be properly washed and cleaned while in its suspended position, as clearly 30 shown in Fig. 3 of the drawings.

As shown in Fig. 2 of the drawings it will be seen that the metal suspension ring 4 is adapted to fit within the inner face of the bowl 6, although entirely independent of 35 the same, the inwardly projecting bends 7 in said ring allows the ring to pass below the plurality of hooks when the hooks and bends are caused to register with each other, and then by giving a short turn to either the 40 right or left the ring will pass beneath the hooks and thus support the bowl in suspended position, and in order to cause the bowl to assume a position to be readily cleaned, such as shown in Fig. 3 it is simply necessary to give the bowl a short turn causing 45 the hooks 16 to register with the bends 7 in the ring thereby allowing the bowl to drop below the fixture to a suitable distance therefrom and remain supported by the 50 chains 19 until properly cleansed.

It will be readily understood that to instantly release the light diffusing bowl from all other parts of the fixture it is simply necessary to turn the bowl to either the right 55 or left until the inward bends 7 in the supporting ring are reached and caused to register with the projecting hooks within the bowl and the bowl will drop to the position shown in Fig. 3.

It will also be apparent that the adjustable supports for each of the lamps permit the change of position of the lamps thus making it possible to either concentrate or distribute the light.

Slight changes in the details of construc-

tion hereinbefore referred to may be resorted to without departing from the spirit of this invention.

Having thus described my invention what I claim and desire to secure by Letters Patent is:—

1. A lighting fixture comprising a metal ring suspended by a plurality of chains, said ring having a plurality of inwardly projecting bends, a suspension member fixedly secured within each projecting bend, an electric lamp removably secured to each suspension member in a position parallel to said ring, and a bowl of light diffusing material supported by said ring when surrounding the ring and when suspended below the ring.

2. A lighting fixture comprising a metal ring suspended by a plurality of chains, said ring having a plurality of inwardly extending bends, a suspension member within each extending bend, said suspension member being provided with a shouldered portion upon which the ring is adapted to rest, and each suspension member being fixedly secured to the ring within each of said bends, and a bowl of light diffusing material supported by said ring but independent thereof.

3. A lighting fixture comprising a metal ring suspended by a plurality of chains, said ring having a plurality of inwardly projecting bends, a suspension member fixedly secured within each of said projecting bends, a plurality of electric lamps removably supported by said ring, and a light diffusing bowl having a metal rim surrounding the upper edge portion thereof, and a plurality of inwardly extended hooks integral with said rim, said bowl being supported by said ring when resting beneath said hooks and within the bowl.

4. A lighting fixture comprising a metal ring suspended by a plurality of chains, said ring having a plurality of inwardly projecting bends, a suspension member fixedly secured within each of said projecting bends, an electric lamp removably secured to the threaded portion of each suspension member in a plane parallel with said ring, and a light diffusing bowl having a metal rim surrounding the upper edge of the bowl, said rim having a plurality of integral inwardly projecting hooks, and a plurality of inwardly projecting members provided with a perforation therethrough adapted to receive one end of a chain, the other end of the chain being attached to the ring, whereby said bowl is supported in its normal position or in a suspended position below said ring.

5. A lighting fixture comprising a metal ring suspended by a plurality of chains, said ring having a plurality of inwardly projecting bends, a suspension member fixedly secured within each of said projecting bends,

said member having an eye portion, a shoul-
dered portion to receive the bend of the
ring, and a depending threaded portion, an
electric lamp removably secured to the said
5 threaded portion in a position parallel to
the ring, and a light diffusing bowl pro-
vided with a metal rim surrounding the
upper edge thereof, said rim having a plu-
rality of integral inwardly extended projec-
10 tions and a plurality of integral inwardly

projecting hooks, said ring normally resting
beneath said hooks and within the inner face
of said bowl.

In testimony whereof I affix my signature
in presence of two witnesses.

ABE SCHOEN.
